HYDRAULIC PRESS

Walter Ferris, Milwaukee, Wis., assignor to The Oilgear Company, Milwaukee, Wis., a corporation of Wisconsin

Application June 18, 1941, Serial No. 398,521

21 Claims. (Cl. 153—21)

This application is a continuation in part of and a substitute for application Serial No. 304,893 filed November 17, 1939.

The invention relates to a bending brake or other hydraulic press which is so wide that a plurality of motors are required to advance and retract the bending beam or platen thereof.

An object of the invention is to provide a hydraulic press in which the beam or platen is operated by a plurality of hydraulic motors and the motors are synchronized to thereby cause both ends of the beam to move upward or downward at the same adjustable speed and to maintain their relative positions when the beam presses against a stationary die or work piece which is located nearer to one end of the beam than to the other end thereof.

Another object is to provide a hydraulic press in which the beam or platen is operated by a plurality of hydraulic motors, the beam or platen may be initially adjusted at an angle to the head or bed of the press, and the motors are synchronized to thereby cause both ends of the beam or platen to move in synchronism and the beam or platen to remain at the adjusted angle throughout the stroke of the press.

Other objects and advantages will appear from the description hereinafter given of a hydraulic press in which the invention is embodied.

According to the invention in its general aspect, a hydraulic press has its beam or platen operated by two hydraulic motors which are connected thereto at or near opposite ends thereof, each motor is energized by liquid supplied thereto by a variable displacement pump, means are provided for regulating the pumps to thereby cause the motors to move the beam or platen, and means are provided for regulating one or both pumps in response to a variation in the movement of one end of the beam or platen relative to the movement of the other end thereof to thereby correct the variation in speed.

According to the invention in another aspect, the beam or platen is connected to the motors by pivotal connections whereby it may be adjusted either at an angle or parallel to the head or bed of the press.

The invention is exemplified by the bending brake shown schematically in the accompanying drawings in which the views are as follows:

Fig. 1 is a diagrammatic view showing the relation of the several parts and the hydraulic circuit of the machine.

Fig. 2 is a sectional plan view taken on the line 2—2 of Fig. 1 and showing the pivotal con-

nections between the bending beam or platen and the shoes which slide upon the columns of the machine.

Fig. 3 is a vertical section on the line 3—3 of Fig. 1 and shows a differential mechanism which forms a part of the control for the pumps.

Fig. 4 is a diagrammatic view showing a modification of the embodiment shown in Fig. 1.

For the purpose of illustration, the invention 10 has been shown embodied in a manually controlled hydraulic press which is employed as a bending brake but it is to be understood that the invention may as readily be embodied in other types of presses and that the presses may be 15 either manually or automatically controlled.

Figs. 1—3

As shown, the bending brake is provided with a bed or base 1 having a bed plate or die holder 2 arranged thereon and two columns 3 and 3^a fixed thereto at opposite ends thereof.

Columns 3 and 3^a have two shoes 4 and 4^a fitted thereon, respectively, and connected by rods 5 and 5^a to pistons 6 and 6^a which are fitted, respectively, in cylinders 7 and 7^a carried by columns 3 and 3^a respectively, each cylinder forming with its piston and the rod thereof a hydraulic motor for sliding a shoe 4 or 4^a vertically upon a column 3 or 3^a.

Shoes 4 and 4^a are bifurcated and support a bending beam or platen 8 which has one end thereof arranged within shoe 4 and journaled upon a pin 9 carried thereby. The other end of beam 8 is arranged within shoe 4^a and has a rectangular slot 10 formed therein to receive a slide 11 which is connected to shoe 4^a by a pin 9^a and bears against the upper and lower edges of slot 10 but is movable longitudinally thereof.

The arrangement is such that any movement 40 or force transmitted to shoe 4 by motor 6—7 will be transmitted through pin 9 to one end of beam 8, and any movement or force transmitted to shoe 4^a by motor 6^a—7^a will be transmitted through pin 9^a and slide 11 to the other end of beam 8. When one end of beam 8 is raised or lowered relative to the other end thereof, the ends of beam 8 will pivot upon pins 9 and 9^a, respectively, and slide 11 will move longitudinally of slot 10.

Liquid for energizing motor 6—7 is supplied 50 thereto by a reversible pump 12 which has its opposite sides connected to opposite ends of cylinder 7 by channels 13 and 14 respectively. Liquid for energizing motor 6^a—7^a is supplied thereto by a reversible pump 12^a which has its

opposite sides connected to opposite ends of cylinder 19 by channels 13^a and 14^a respectively.

Pumps 12 and 12^a may be of the type shown in Patent No. 2,114,005. Such a pump has a displacement varying member or slide block which is shiftable in one direction or the other from a central or neutral position to cause the pump to deliver liquid in a direction and at a rate determined by the direction and the distance the slide block is offset from its neutral position. When the slide block is in its neutral position, the pump will be at zero stroke and no liquid will be delivered thereby. The slide block is ordinarily shifted by hydraulic actuators under the control of a rotary follow-up valve as shown in said patent but, in order that the valve and its operating mechanism may appear in the same plane, each slide block has been shown as being adapted to be shifted by ordinary hydraulic servo-motors under the control of a reciprocating valve which is connected by means of a follow-up mechanism to its actuator and to the slide block.

As shown, pump 12 is provided with a slide block 15 which is adapted to be shifted toward the left, or in a direction to cause pump 12 to discharge liquid into channel 13, by a piston 16 which is connected thereto or in contact therewith and fitted in a cylinder 17 carried by the pump casing. Slide block 15 is adapted to be shifted toward the right, or in a direction to cause pump 12 to discharge liquid into channel 14, by a piston 18 which is connected thereto or in contact therewith and fitted in a cylinder 19 carried by the pump casing, the effective pressure area of piston 18 being considerably greater than that of piston 16.

Liquid for operating servo-motors 16-17 and 18-19 is supplied by a gear pump 20 which is ordinarily driven in unison with pump 12 and arranged in the casing thereof according to the usual practice but which has been shown as being separate therefrom. Also, gear pump 20 has been shown as providing liquid for energizing the servo-motors of both of pumps 12 and 12^a but each of those pumps may have a gear pump for energizing its servo-motor.

As shown, gear pump 20 draws liquid from a reservoir 21 and discharges it into a branched supply channel 22 having one of its branches connected to cylinder 17 so that piston 16 constantly tends to shift slide block 15 toward the left.

The liquid discharged by gear pump 20 in excess of requirements is exhausted into reservoir 21 through a relief valve 23 which is connected to channel 22 and enables gear pump 20 to maintain therein a uniform pressure great enough to enable piston 16 to exert a force considerably in excess of the force required to shift slide block 15 toward the left when cylinder 19 is open to drain and to enable piston 18 to exert a force considerably in excess of the force required to shift slide block 15 toward the right against the resistance of piston 16 when cylinder 19 is open to supply channel 22.

The flow of liquid to and from cylinder 19 is under the control of a valve 24 which is fitted in the bore of a valve casing 25 having three annular grooves or ports 26, 27 and 28 formed therein. Port 26 and the right end of valve casing 25 are connected to a drain channel 29, port 27 is connected to cylinder 19 by channel 30 and port 28 has a branch of supply channel 22 connected thereto.

Control valve 24 has been shown as having its center piston of exactly the same width as port 27 so that, when valve 24 is in its central or neutral position, the center piston of valve 24 blocks

5 port 27 and its edges make a line and line contact with the edges of port 27. Blocking port 27 prevents liquid from flowing to or escaping from cylinder 19 so that slide block 15 is held stationary against the force exerted thereon by piston 16. When valve 24 is shifted toward the left, liquid from gear pump 20 may flow through channel 22, valve casing 25 and channel 30 to cylinder 19 and cause piston 18 to move slide block 15 toward the right. When valve 24 is 10 shifted toward the right, liquid may escape from cylinder 19 through channel 30 and valve casing 25 into drain channel 29, thereby permitting servo-motor 16-17 to move slide block 15 toward the left.

20 In practice however, such a control valve ordinarily has a center piston which is slightly narrower than the port which it controls but the difference between the width of the piston and the width of the port is so slight that it cannot

25 be shown in the drawings. If the center piston is slightly narrower than port 27, its edges will

be equally spaced from the edges of port 27 when valve 24 is in its neutral position, thereby permitting liquid to flow from channel 22 into port

30 27 and liquid to flow from port 27 into drain channel 29 at the same rate so that there is no

flow to or from cylinder 19.

The advantage of such a construction is that, if the valve piston and the port are the same

35 width, a given movement of the valve will uncover the port the same amount while, if the piston is narrower than the port and the valve is moved a distance equal to one half the difference between the width of the piston and the

40 width of the port, the port will be uncovered by an amount equal to twice the distance that the valve was moved so that liquid is directed to or permitted to escape from the stroke adjusting

45 servo-motor at a rate twice as great as the rate would be if the piston and port were of the same width.

Pump 12^a has been shown as being of the same type as pump 12 and as being controlled by the same kind of a valve so that a description thereof 50 is unnecessary, corresponding parts being indicated by corresponding reference numerals with the exponent ^a added to the reference numerals applied to pump 12 and its valve.

Valves 24 and 24^a are both actuated manually 55 to start, reverse or to change the speed of the press and are then automatically adjusted in response to the movement of one end of beam 8 varying relative to the movement of the other end of beam 8 as reflected through a three legged differential 31 which will be presently described. Differential 31 has its first and second legs driven, respectively, from opposite ends of beam 8 and its third leg connected to a lever 32 which is normally stationary but which will swing upon 60 its pivot in response to one end of beam 8 moving relative to the other end thereof. For example, if beam 8 is initially adjusted parallel to bed plate 2, any departure of beam 8 from parallelism therewith will cause lever 32 to swing upon its pivot.

65 As shown, valves 24 and 24^a are adjusted manually by means of a pedal 33 arranged upon one end of a lever 34 which is pivoted intermediate its ends upon a stationary bracket 35. The 70 other end of lever 34 is connected by a rod 36

to the horizontal arm of a bell crank lever 37 which is pivoted upon a stationary pin 38. The vertical arm of lever 37 is connected to the lower end of a floating lever 38 which is pivoted intermediate its ends upon a pin 40 carried by a rod 41 which is movable with slide block 15. In order to simplify the view, rod 41 has been shown attached to piston 18 but in practice such a rod is extended through the wall of the pump casing and attached directly to slide block 15.

The upper end of lever 39 is connected by a link 42 to a floating lever 43 intermediate the ends thereof. Lever 43 has its lower end connected to the stem of valve 24 and its upper end connected to differential lever 32 by a discon- 10 nectible mechanism comprising a rocker 44 having its upper end pivoted upon a pin 45 carried by a stationary support 46 and its lower end provided with a notch 47 which is normally in alinement with a hole 48 formed in support 46, a link 49 which connects the upper end of lever 43 to rocker 44, and a link 50 which connects lever 32 to rocker 44 by means of pins 51 and 52 respectively.

Pin 52 may be removed from the end of link 50 and inserted through notch 47 into hole 48, to hold rocker 44 and the upper end of lever 43 stationary, and link 50 may then be supported upon a flange 53 on support 46 so that it may 30 slide thereon when differential 31 operates as will presently be explained.

The vertical arm of lever 37 is also connected by a link 54 to the lower end of a lever 55 pivoted intermediate its ends upon a pin 56 arranged in the end of a rod 57 which is movable with a slide block 15 and has been shown attached to piston 18. The upper end of lever 55 is connected by a link 58 to the lower end of a lever 59 which is connected intermediate its 40 ends to valve 24 by a link 60 and has its upper end pivoted upon pin 51.

In order to simplify the drawing, the levers of the mechanism for shifting valves 24 and 24^a have been shown out of proportion and connected by closely fitted pin joints but it is to be understood that the levers are properly proportioned and that means, such as a pin and slot connection or an additional joint, is provided where necessary to compensate for the rocking movement of a lever such as the rocking movement of lever 37.

In order that beam 8 may be stopped at the end of its up stroke in a manner to be presently explained, control rod 36 extends through an arm 61 which is fixed to shoe 4^a and a collar 62 is clamped upon rod 36 in such a position that it will be engaged by arm 61 when beam 8 approaches the limit of its up stroke. Collar 62 is held against arm 61 when the machine is idle by rod 36 being continuously urged downward in any suitable manner such as by means of a spring 63 arranged beneath foot lever 34.

Differential 31 (Figs. 1 and 3) is provided with a stationary shaft 64 which is arranged in a suitable housing (not shown) and has lever 32 pivoted thereon. The upper end of lever 32 carries a stub shaft 65 having a planet pinion 66 journaled thereon and in mesh with a sun gear 67 which is fixed upon a sleeve 68 journaled upon shaft 64. Sleeve 68 has a bevel pinion 69 fixed thereto or formed integral therewith and in mesh with a bevel pinion 70 which is fixed upon one end of a horizontal shaft 71.

Sleeve 68 has journaled thereon a compound 75

gear 72 consisting of an internal spur gear and an external bevel gear formed integral with each other. Gear 72 has its internal teeth in mesh with the teeth of planet pinion 66 and its external teeth in mesh with the teeth of a bevel pinion 73 which is fixed upon one end of a horizontal shaft 71^a.

The several parts of differential 31 are so proportioned that, when shafts 71 and 71^a are rotated at the same speed in the same direction gears 67 and 72 will transmit rotary motion to planet pinion 66 at the same rate, so that shaft 68 remains stationary and transmits no motion to lever 32 but, when one shaft 71 or 71^a rotates faster than the other, gears 67 and 72 will transmit rotary motion to pinion 66 at different rates and thereby cause it to travel around sun gear 67 in one direction or the other and swing lever 32 in one direction or the other.

Shaft 71 is journaled in suitable bearings and connected through intermeshing bevel gears 75 and 76 to the upper end of a vertical shaft 77 which is provided at its lower end with a bevel pinion 78 and journaled near its lower end in a stationary bearing bracket 79 shown as being carried by cylinder 7. Pinion 78 meshes with a bevel gear 80 fixed upon one end of a shaft 81 which is journaled in bracket 79 and has a spur pinion 82 fixed upon its other end. Pinion 82 meshes with a vertical rack 83 which is movable vertically with the right end of beam 8 as by being attached to shoe 4.

The mechanism for transmitting motion from the left end of beam 8 to shaft 71^a may be exactly the same as but opposite hand to the above described mechanism for transmitting motion from the right end of beam 8 to shaft 71 but it has been shown provided with means for enabling one end of beam 8 to be moved relative to the other end thereof.

As shown, shaft 71^a is connected through bevel gears 75^a and 76^a to the upper end of a shaft 77^a having the lower end thereof journaled in a bearing bracket 79^a and provided with a bevel pinion 78^a which meshes with a bevel gear 80^a fixed upon one end of a shaft 81^a having a pinion 82^a fixed upon the other end thereof and meshing with a rack 83^a carried by shoe 4^a.

It will be obvious that the above described mechanisms will cause shafts 71 and 71^a to be rotated in one direction in response to upward movement of beam 8 and cause shafts 71 and 71^a to be rotated in the opposite direction in response to downward movement of beam 8.

Since the slack or lost motion inherent in all gear trains would prevent pumps 12 and 12^a from being accurately controlled, lever 32 is constantly urged in one direction by a spring 34 having sufficient strength to keep all lost motion out of differential 31 and the gearing and linkage connected thereto. Also, the ratios of the gearing and linkage are such that a micrometric movement of one end of beam 8 relative to the other end thereof will cause a substantial movement of control valves 24 and 24^a.

In order that beam 8 may be adjusted either parallel to base 1 or at an angle thereto, shaft 77^a is divided into two sections which are normally connected to each other by a separable coupling 85, the upper section of shaft 77^a extends through an arm 86 carried by bearing bracket 79^a, and a set screw 87 is threaded into arm 86 and adapted to be advanced into contact with the upper section of shaft 77^a to prevent it from rotating when coupling 85 is disengaged.

Operation

Assuming that the press has been stopped with the parts in the positions shown and that the pumps are running, the press will operate as follows:

With the press idle, differential 31 will hold lever 32, link 50, rocker 44 and link 49 stationary and pumps 12 and 12^a will deliver just enough liquid to prevent beam 8 from descending.

To start the press, pedal 33 is depressed to rock lever 34 upon bracket 35 and cause rod 36 to rock lever 37 upon pin 38 in a counterclockwise direction. Lever 37 will move link 54 and the lower ends of levers 39 and 55 toward the left to cause levers 39 and 55 to pivot upon pins 40 and 56 respectively. The upper end of lever 39 and link 42 will move toward the right and cause lever 43 to pivot upon the end of link 49 and shift valve 24^a toward the right. The upper end of lever 55 and link 58 will swing lever 59 upon pin 51 to cause link 60 to shift valve 24 toward the right.

Shifting valves 24 and 24^a toward the right permits liquid to escape from cylinders 19 and 19^a so that the liquid in cylinders 17 and 17^a will move pistons 16 and 16^a and slide blocks 15 and 15^a toward the left, thereby causing pumps 12 and 12^a to discharge liquid into channels 13 and 13^a respectively.

As slide blocks 15 and 15^a move toward the left, rods 41 and 57 move with them and swing the upper ends of levers 39 and 55 toward the left so that valves 24 and 24^a are returned to their neutral positions substantially as soon as movement of pedal 33 ceases at which time slide blocks 15 and 15^a will each have moved through a distance proportional to the distance through which pedal 33 was moved.

The liquid discharged by pumps 12 and 12^a will flow through channels 13 and 13^a, respectively, to the upper ends of cylinders 7 and 7^a and cause pistons 6 and 6^a to move beam 8 downward and thereby cause shafts 71 and 71^a to be rotated due to pinions 82 and 82^a being rotated by racks 83 and 83^a which move downward with beam 8.

As long as both ends of beam 8 move downward at the same speed, shafts 71 and 71^a will be rotated at the same speed and cause planet pinion 66 to rotate on a stationary axis so that no motion is imparted to valves 24 and 24^a.

However, if the right end of beam 8 should start to run ahead of the left end thereof, shaft 71 would start to rotate faster than shaft 71^a and thereby cause planet pinion 66 to start to move around sun gear 67 in a clockwise direction as viewed in Fig. 1. Planet pinion 66 would swing lever 32 upon shaft 64 and cause it to shift valve 24 toward the left so that liquid from channel 22 would flow through valve casing 25 to cylinder 19 and move slide block 15 toward the right to reduce the displacement and volumetric delivery of pump 12 and thereby reduce the speed of the right end of beam 8. At the same time, lever 32 and link 50 would swing rocker 44 upon pin 45 and cause link 49 to move the upper end of lever 43 toward the left. Lever 43 would pivot upon the end of link 42 and shift valve 24^a toward the right to open cylinder 19^a to drain channel 28^a and permit the pressure in cylinder 17^a to move piston 16^a and slide block 15^a toward the left to increase the displacement and volumetric delivery of pump 12^a and thereby increase the speed of piston 6^a to cause the left end of beam 8

to catch up with the right end thereof at which time movement of lever 32 would cease and the follow-up mechanism would have returned valves 24 and 24^a to their neutral positions and beam 8 would continue downward at the adjusted speed.

If the right end of beam 8 should start to lag behind the left end thereof, the control mechanism would operate in the above described manner but in the opposite direction to correct the variation in the movements of the two ends of beam 8. That is, as soon as the right end of beam 8 started to lag behind the left end thereof, shaft 71 would start to rotate slower than shaft 71^a and thereby cause planet pinion 66 to start to move around sun gear 67 in a counterclockwise direction as viewed in Fig. 1. Planet pinion 66 would swing lever 32 upon shaft 64 and cause valve 24 to be shifted toward the right and valve 24^a to be shifted toward the left to increase the displacement of pump 12 and the speed of motor 6-7 and to decrease the displacement of pump 12^a and the speed of motor 6^a-7^a until the two ends of beam 8 were even and moving at the same speed.

When the down stroke of beam 8 has been completed, pedal 33 is released to permit control rod 36 to descend and cause valves 24 and 24^a to be shifted toward the left from their neutral positions so that liquid from channel 22 can enter cylinders 19 and 19^a and cause pistons 18 and 18^a to shift slide blocks 15 and 15^a toward the right beyond their neutral positions and thereby cause pumps 12 and 12^a to discharge liquid into channels 14 and 14^a respectively.

As slide blocks 15 and 15^a move toward the right, rods 41 and 57 move with them and swing the upper ends of levers 39 and 55 toward the right so that valves 24 and 24^a are returned to their neutral positions substantially as soon as movement of pedal 33 ceases at which time slide blocks 15 and 15^a will each have moved through a distance proportional to the distance through which pedal 33 was moved.

The liquid discharged by pumps 12 and 12^a will flow through channels 14 and 14^a, respectively, to the lower ends of cylinders 7 and 7^a and cause pistons 6 and 6^a to move beam 8 upward and thereby cause shafts 71 and 71^a to be rotated in the previously described manner but in the opposite direction.

As long as both ends of beam 8 move upward at the same speed, shafts 71 and 71^a will be rotated at the same speed and cause planet pinion 66 to rotate on a stationary axis so that no motion is imparted to valves 24 and 24^a but, if the right end of beam 8 should tend to lag behind or move ahead of the left end thereof, any material movement of one end of beam 8 relative to the other end thereof would be prevented by differential 31 and the associated parts which would operate as explained above.

When beam 8 approaches the limit of its up stroke, arm 61 on shoe 4^a engages collar 62 and raises control rod 36 which will shift valves 24 and 24^a toward the right to cause slide blocks 15 and 15^a to move toward the left until pumps 12 and 12^a are at zero stroke at which time upward movement of beam 8 ceases and rods 41 and 57 will have returned valves 24^a and 24 to their neutral positions.

If pin 52 is removed to disconnect lever 32 from valve 24^a, link 50 will lower upon flange 53 on which it may slide when differential 32 operates, and pin 52 is inserted through notch 47 into hole 48 to

Fig. 4

hold rocker 44 and the upper end of lever 43 stationary, the press will operate in the above described manner except that valve 24^a will be shifted only by pedal 33 so that the speed of beam 8 will be determined by the speed of motor 6^a—7^a, and any variation in the speed of the right end of beam 8 relative to the speed of the left end thereof will cause differential 31 to adjust valve 24 only to vary the displacement of pump 12 to thereby correct such variation in speed.

This arrangement is satisfactory if beam 8 is to operate upon work placed under the center of beam 8 or symmetrically on both sides of said center, or placed on the left side only of said center but, if the work were arranged at the right side only of its center and beam 8 should be pressed against the work until motor 6—7 stalled, motor 6^a—7^a would continue to move the left end of beam 8 downward until stopped by the operator or until it stalled.

Since there is no assurance that short pieces of work would always be placed either symmetrically about the center or under the left half of beam 8, both of valves 24 and 24^a are operated by differential 31 as explained above.

It is sometimes desired to bend a work piece a greater amount at one side or end than at the other side or end thereof. Instead of providing special dies for this purpose as is customary, beam 8 may be adjusted at an angle to bed 1 so that ordinary straight dies may be employed.

Adjustment of beam 8 to any desired angle may be accomplished by removing pin 52 and permitting link 50 to be supported upon flange 53, inserting pin 52 through notch 47 into hole 48 to hold rocker 44 stationary, advancing set screw 87 into engagement with the upper section of shaft 71^a to prevent it from being rotated, then disengaging clutch 85, and then depressing pedal 33 slightly to cause motors 6—7 and 6^a—7^a to move beam 8 downward in the above described manner at slow speed.

Motor 6^a—7^a will continue to move the left end of beam 8 downward as long as pedal 33 is held down but, as soon as the right end of beam 8 starts downward, shaft 71 will be rotated as explained above and cause differential 31 to shift valve 24 to reduce the displacement of pump 12. Since shaft 71^a is held stationary by set screw 87 and differential 31 is prevented from moving valve 24^a, the displacement of pump 12 will be reduced to zero so that motor 6—7 will hold the right end of beam 8 stationary.

When the left end of beam 8 has been lowered to the desired point, pedal 33 is returned to its neutral position to stop further downward movement of the left end of beam 8, collar 62 is moved downward into contact with arm 61, clutch 85 is re-engaged, set screw 87 is retracted out of contact with shaft 71^a, and pin 52 is removed from hole 48 and reinserted through link 50 into rocker 44.

If it is desired to incline beam 8 in the opposite direction, the same procedure is followed except that pedal 33 is raised slightly so that the above described operation is reversed it being understood that collar 62 should be first moved out of engagement with arm 61 in order to permit rod 36 to descend.

Regardless of whether beam 8 is parallel to bed 1 or inclined in one direction or the other, the press will operate in the above described manner and both ends of beam 8 will be moved through the same distance during both the down stroke and the up stroke of beam 8.

5 The machine may be employed to operate upon work which does not require that its beam or platen be maintained parallel to the bed or at a predetermined angle thereto, that is, one end of the beam or platen may advance slightly ahead of the other end without affecting the quality of the work.

10 In such a case, it is not necessary to start both the motors simultaneously by shifting the slide block of both pumps simultaneously when initiating a stroke of the beam or platen. It is only necessary to start one motor and cause the other motor to follow it.

15 This may be accomplished by omitting disconnecting mechanism 44—53 and connecting link 42 directly to the stem of valve 24^a, and omitting link 54 and pivoting the lower end of lever 55 upon a stationary pin 90 as shown in Fig. 4. 20 Then when pedal 33 is depressed, motor 6^a—7^a will start to move the left end of beam 8 downward in the previously described manner but, as soon as the left end of beam 8 starts to move, gear train 75^a—83^a will rotate shaft 71^a and thereby cause differential 31 to shift pilot valve 24 which will cause slide block 15 of pump 12 to be shifted so that pump 12 will deliver liquid to motor 6—7 and cause it to move the right end of beam 8 downward as previously explained. 25 Due to the very large ratio between gear 75^a and rack 83^a, the lower end of beam 8 need only a small fraction of an inch to effect operation of motor 6—7.

30 The machine will operate in exactly the same manner as the machine shown in Fig. 1 except that one motor starts and the other motor follows it instead of the motors starting simultaneously. This results in slight departures from parallelism between the various positions of the beam.

35 The press described herein is susceptible of various other modifications and adaptations without departing from the scope of the invention which is hereby claimed as follows:

40 1. The combination, with a plurality of reciprocating hydraulic motors, of an equal number of reversible pumps each hydraulically connected to one of said motors and having hydraulic means for varying its displacement and a valve for controlling said hydraulic means to thereby control the pump, means for supplying liquid through said valves to said hydraulic means, means for shifting said valves in one direction or the other simultaneously to cause said pumps to deliver liquid to one end or the other of said motors and thereby cause said motors to operate simultaneously in one direction or the other, and means responsive to the speed of one of said motors varying relative to the speed of another motor for further adjusting at least one of said valves to thereby correct said variation in speed.

45 2. The combination, with two reciprocating hydraulic motors, of two reversible pumps each hydraulically connected to one of said motors and having hydraulic means for varying its displacement and a valve for controlling said hydraulic means to thereby control the pump, means for supplying liquid through said valves to said hydraulic means, means for shifting said valves in one direction or the other simultaneously to cause said pumps to deliver liquid to one end or the other of said motors and thereby cause said motors to operate simultaneously in one direction or the other, and means responsive to the

speed of one of said motors varying relative to the speed of another motor for further adjusting said valves to decrease the speed of said one motor and increase the speed of said other motor until said variation in speed is corrected.

3. The combination, with a plurality of hydraulic motors, of an equal number of reversible pumps each hydraulically connected to one of said motors and having a member for varying its displacement and hydraulic means for shifting said member, means for supplying liquid to the hydraulic means of each pump including a valve for controlling that pump, said valves being normally in neutral positions and shiftable therefrom to effect operation of said hydraulic means, means for adjusting said valves including means for shifting said valves in one direction or the other simultaneously to cause said pumps to deliver liquid to one port or the other of said motors and thereby cause said motors to operate simultaneously in one direction or the other and a follow-up mechanism for moving each valve toward its neutral position in response to movement of the displacement varying member of the pump controlled by that valve, and means responsive to the speed of one of said motors varying relative to the speed of another motor for further adjusting at least one of said valves to thereby correct said variation in speed.

4. The combination, with two hydraulic motors, of two reversible pumps each hydraulically connected to one of said motors and having a member for varying its displacement and hydraulic means for shifting said member, means for supplying liquid to the hydraulic means of each pump including a valve for controlling that pump, said valves being normally in neutral positions and shiftable therefrom to effect operation of said hydraulic means, means for adjusting said valves including means for shifting said valves in one direction or the other simultaneously to cause said pumps to deliver liquid to one port or the other of said motors and thereby cause said motors to operate simultaneously in one direction or the other and a follow-up mechanism for moving each valve toward its neutral position in response to movement of the displacement varying member of the pump controlled by that valve, and means responsive to the speed of one of said motors varying relative to the speed of another motor for further adjusting said valves to decrease the speed of said one motor and increase the speed of said other motor until said variation in speed is corrected.

5. The combination, with a first and a second hydraulic motor, of a first and a second pump for energizing said first and second motors respectively, each of said pumps having an element for varying its displacement and hydraulic means for shifting said element, means for supplying liquid to said hydraulic means including a first valve for controlling said first pump and a second valve for controlling said second pump, means for adjusting said valves to thereby control the operation of said motors, a three-legged differential having a first and a second leg thereof driven in response to movements created by said first and second motors respectively whereby the third leg thereof rotates in response to the speed of one motor varying from the speed of the other motor, and means responsive to rotation of said third leg for further adjusting at least one of said valves to thereby correct said variation in speed.

6. In a machine having a stationary member, a platen normally arranged parallel to said mem-

ber and power means arranged at opposite sides of the center of said platen for reciprocating said platen toward and from said member, the combination of means for pivotally connecting said platen to each of said power means, and control means responsive to uneven travel of said platen for adjusting said power means to restore even travel of said platen and including means for adjusting said control means to cause said power means to adjust said platen at an angle to said member.

7. In a machine, the combination of two reciprocating hydraulic motors spaced from each other, a platen normally arranged at right angles to the axes of said motors and pivotally connected to said motors to be reciprocated thereby, two reversible pumps each hydraulically connected to one of said motors and having hydraulic means for varying its displacement and a valve for controlling said hydraulic means to thereby control the pump, means for supplying liquid through said valves to said hydraulic means, means for causing one of said motors to move one end of said platen relative to the other end thereof to change the angle between said platen and the axes of said motors, means for shifting said valves in one direction or the other simultaneously to cause said pumps to deliver liquid to one end or the other of said motors and thereby cause said motors to operate simultaneously in one direction or the other, and means responsive to the speed of one of said motors varying relative to the speed of the other motor for further adjusting at least one of said valves to thereby correct said variation in speed.

8. In a machine, the combination of two reciprocating hydraulic motors spaced from each other, a platen normally arranged at right angles to the axes of said motors and pivotally connected to said motors to be reciprocated thereby, two reversible pumps each hydraulically connected to one of said motors and having hydraulic means for varying its displacement and a valve for controlling said hydraulic means to thereby control the pump, means for supplying liquid through said valves to said hydraulic means, means for causing one of said motors to move one end of said platen relative to the other end thereof to change the angle between said platen and the axes of said motors, means for shifting said valves in one direction or the other simultaneously to cause said pumps to deliver liquid to one end or the other of said motors and thereby cause said motors to operate simultaneously in one direction or the other, and means responsive to the speed of one of said motors varying relative to the speed of the other motor for further adjusting said valve to decrease the speed of said one motor and increase the speed of said other motor until said variation in speed is corrected.

9. In a machine, the combination of two reciprocating hydraulic motors spaced from each other, a platen normally arranged at right angles to the axes of said motors and pivotally connected to said motors to be reciprocated thereby, two reversible pumps each hydraulically connected to one of said motors and having a member for varying its displacement and hydraulic means for shifting said member, means for supplying liquid to the hydraulic means of each pump including a valve for controlling that pump, means for causing one of said motors to move one end of said platen relative to the other end thereof to change the angle between said platen

and the axes of said motors, said valves being normally in neutral positions and shiftable therefrom to effect operation of said hydraulic means, means for adjusting said valves including means for shifting said valves in one direction or the other simultaneously to cause said pumps to deliver liquid to one end or the other of said motors and thereby cause said motors to operate simultaneously in one direction or the other and a follow-up mechanism for moving each valve toward its neutral position in response to movement of the displacement varying member of the pump controlled by that valve, and means responsive to the speed of one of said motors varying relative to the speed of the other motor for further adjusting at least one of said valves to thereby correct said variation in speed.

10. A machine, comprising a reciprocable member, two spaced apart guides for guiding said member, separate means for connecting one end of said member to one of said guides and the other end of said member to the other of said guides and adapted to permit one end of said member to be advanced a substantial distance ahead of the other end thereof, a first hydraulic motor for reciprocating one end of said member, a second hydraulic motor for reciprocating the other end of said member, a first and a second pump for energizing said first and second motors respectively, each of said pumps having an element for varying its displacement and hydraulic means for shifting said element, means for supplying liquid to said hydraulic means including a first valve for controlling said first pump and a second valve for controlling said second pump, means for adjusting said valves to thereby control the operation of said motors, a three-legged differential having one of its legs driven by said first motor and a second leg driven by said second motor whereby its third leg rotates in response to the ends of said member moving through different distances, means responsive to rotation of said third leg for further adjusting at least one of said valves to thereby maintain said motors in synchronism, and means for causing one of said motors to operate independently of the other and move one end of said member relative to the other end thereof to thereby adjust the angular position of said member relative to said guides.

11. A machine, comprising a frame, a member guided by said frame, a first and a second motor connected to said member near opposite ends thereof to reciprocate the same, a first and a second pump for energizing said first and second motors respectively, each of said pumps having an element for varying its displacement and hydraulic means for shifting said element, means for supplying liquid to said hydraulic means including a first valve for controlling said first pump and a second valve for controlling said second pump, a three-legged differential having one of its legs driven by said first motor and a second leg driven by said second motor whereby its third leg moves in response to the ends of said member moving through different distances, means for adjusting said valves simultaneously, and means for further adjusting at least one of said valves in response to movement of the third leg of said differential to thereby correct any variation in the movement of one end of said member relative to the movement of the other end of said member.

12. A machine, comprising a frame, a member 75

guided by said frame, a first and a second motor connected to said member near opposite ends thereof to reciprocate the same, a first and a second pump for energizing said first and second motors respectively, each of said pumps having an element for varying its displacement and hydraulic means for shifting said element, means for supplying liquid to said hydraulic means including a first valve for controlling said first pump and a second valve for controlling said second pump, said valves normally being in neutral positions and shiftable therefrom to effect operation of said hydraulic means, a three-legged differential having one of its legs driven by said first motor and a second leg driven by said second motor whereby its third leg moves in response to the ends of said member moving through different distances, means for adjusting said valves including means for shifting said valves simultaneously from their neutral positions and a follow-up mechanism for moving each valve toward its neutral position in response to movement of the displacement varying element of the pump controlled by that valve, and means for further adjusting at least one of said valves in response to movement of the third leg of said differential to thereby correct any variation in the movement of one end of said member relative to the movement of the other end of said member.

13. A machine, comprising a frame, a member guided by said frame, a first and a second motor connected to said member near opposite ends thereof to reciprocate the same, a first and a second pump for energizing said first and second motors respectively, each of said pumps having an element for varying its displacement and hydraulic means for shifting said element, means for supplying liquid to said hydraulic means including a first valve for controlling said first pump and a second valve for controlling said second pump, said valves normally being in neutral positions and shiftable therefrom to effect operation of said hydraulic means, a three-legged differential having one of its legs driven by said first motor and a second leg driven by said second motor whereby its third leg moves in response to the ends of said member moving through different distances, an actuator, a first follow-up mechanism for connecting said first valve to said actuator and to the element of said first pump, a second follow-up mechanism for connecting said second valve to said actuator and to the element of said second pump, means for operating said actuator to cause said valves to be simultaneously shifted from their neutral positions, said valves being moved toward their neutral positions by said follow-up mechanisms in response to movement of said displacement varying elements, and means for connecting said follow-up mechanisms to the third leg of said differential so that said valves are further adjusted in response to movement of said third leg to thereby correct any variation in the movement of one end of said member relative to the movement of the other end of said member.

14. A machine, comprising a reciprocable member, two spaced apart guides for guiding said member, separate means for connecting one end of said member to one of said guides and the other end of said member to the other of said guides and adapted to permit one end of said member to be advanced a substantial distance ahead of the other end thereof, a first hydraulic motor for reciprocating one end of said member,

a second hydraulic motor for reciprocating the other end of said member, a first and a second pump for energizing said first and second motors respectively, each of said pumps having an element for varying its displacement and hydraulic means for shifting said element, means for supplying liquid to said hydraulic means including a first valve for controlling said first pump and a second valve for controlling said second pump, means for adjusting said valves simultaneously to thereby cause said motors to move both ends of said member in unison, means for causing one of said motors to operate independently of the other and move one end of said member relative to the other end thereof, a three-legged differential having one of its legs driven by said first motor and a second leg driven by said second motor whereby its third leg moves in response to the ends of said member moving through different distances, and means for further adjusting at least one of said valves in response to movement of the third leg of said differential to thereby cause said motors to move both ends of said member in synchronism regardless of whether one end of said member is even with or ahead of the other end of said member.

15. A machine, comprising a reciprocable member, two spaced apart guides for guiding said member, a first shoe slidable upon one of said guides, a second shoe slidable upon the other guide, means for pivotally connecting said shoes to said member near opposite ends thereof, a first and a second hydraulic motor for reciprocating said first and second shoes respectively upon said guides to thereby reciprocate said member, a first and a second pump for energizing said first and second motors respectively, each of said pumps having an element for varying its displacement and hydraulic means for shifting said element, means for supplying liquid to said hydraulic means including a first valve for controlling said first pump and a second valve for controlling said second pump, means for adjusting said valves simultaneously to thereby cause said motors to move both ends of said member in unison, means for causing one of said motors to operate independently of the other and move one of said shoes relative to the other to thereby cause said member either to be perpendicular to said guides or to be inclined thereto, a three-legged differential having one of its legs driven by said first motor and a second leg driven by said second motor whereby its third leg moves in response to the ends of said member moving through different distances, and means for further adjusting at least one of said valves in response to movement of the third leg of said differential to thereby cause said motors to move both ends of said member in synchronism regardless of whether one end of said member is even with or ahead of the other end of said member.

16. A machine, comprising a reciprocable member, two spaced apart guides for guiding said member, a first shoe slidable upon one of said guides, a second shoe slidable upon the other guide, means for pivotally connecting said shoes to said member near opposite ends thereof, a first and a second hydraulic motor for reciprocating said first and second shoes respectively upon said guides to thereby reciprocate said member, a first and a second pump for energizing said first and second motors respectively, each of said pumps having an element for

varying its displacement and hydraulic means for shifting said element, means for supplying liquid to said hydraulic means including a first valve for controlling said first pump and a second valve for controlling said second pump, said valves normally being in neutral positions and shiftable therefrom to effect operation of said hydraulic means, means for adjusting said valves including means for shifting said valves simultaneously from their neutral positions and a follow-up mechanism for moving each valve toward its neutral position in response to movement of the displacement varying element of the pump controlled by that valve to thereby cause said motors to move both ends of said member in unison, means for causing one of said motors to operate independently of the other and move one end of said shoes relative to the other to thereby cause said member either to be perpendicular to said guides or to be inclined thereto, a three-legged differential having one of its legs driven by said first motor and a second leg driven by said second motor whereby its third leg moves in response to the ends of said member moving through different distances, and means for further adjusting at least one of said valves in response to movement of the third leg of said differential to thereby cause said motors to move both ends of said member in synchronism regardless of whether one end of said member is even with or ahead of the other end of said member.

17. A machine, comprising a reciprocable member, two spaced apart guides for guiding said member, a first shoe slidable upon one of said guides, a second shoe slidable upon the other guide, means for pivotally connecting said shoes to said member near opposite ends thereof, a first and a second hydraulic motor for reciprocating said first and second shoes respectively upon said guides to thereby reciprocate said member, a first and a second pump for energizing said first and second motors respectively, each of said pumps having an element for varying its displacement and hydraulic means for shifting said element, means for supplying liquid to said hydraulic means including a first valve for controlling said first pump and a second valve for controlling said second pump, said valves normally being in neutral positions and shiftable therefrom to effect operation of said hydraulic means, an actuator, a first follow-up mechanism for connecting said first valve to said actuator and to the element of said first pump, a second follow-up mechanism for connecting said second valve to said actuator and to the element of said second pump, means for operating said actuator to cause said valves to be simultaneously shifted from their neutral positions to thereby cause said motors to move both ends of said member in unison, said valves being moved toward their neutral positions by said follow-up mechanisms in response to movement of said displacement varying elements, and means for connecting at least one of said follow-up mechanisms to the third leg of said differential so that at least one of said valves is further adjusted in response to movement of said third leg to thereby cause said motors to move both ends of said member in synchronism regardless of whether one end of said member is even with or ahead of the other end of said member.

18. A machine, comprising a reciprocable member, two spaced apart guides for guiding said

member, separate means for connecting one end of said member to one of said guides and the other end of said member to the other of said guides and adapted to permit one end of said member to be advanced a substantial distance ahead of the other end thereof, a first hydraulic motor for reciprocating one end of said member, a second hydraulic motor for reciprocating the other end of said member, a first and a second pump for energizing said first and second motors respectively, each of said pumps having an element for varying its displacement and hydraulic means for shifting said element, means for supplying liquid to said hydraulic means including a first valve for controlling said first pump and a second valve for controlling said second pump, means for adjusting said valves simultaneously to thereby cause said motors to move both ends of said member in unison, a three-legged differential, two drives for driving two legs of said differential from opposite ends of said member to thereby cause the third leg of said differential to move in response to the ends of said member moving through different distances, means for further adjusting at least one of said valves in response to movement of the third leg of said differential to thereby correct any variation in the movement of one end of said member relative to the movement of the other end of said member, and means for causing one motor to operate independently of the other motor and move one end of said member relative to the other end thereof including means for restraining one leg of said differential from rotating and means for rendering ineffective the drive connected to that leg.

19. A machine, comprising a reciprocable member, two spaced apart guides for guiding said member, a first shoe slideable upon one of said guides, a second shoe slideable upon the other guide, means for pivotally connecting said shoes to said member near opposite ends thereof, a first and a second hydraulic motor for reciprocating said first and second shoes respectively upon said guides to thereby reciprocate said member, a first and a second pump for energizing said first and second motors respectively, each of said pumps having an element for varying its displacement and hydraulic means for shifting said element, means for supplying liquid to said hy-

- draulic means including a first valve for controlling said first pump and a second valve for controlling said second pump, means for adjusting said valves simultaneously to thereby cause said motors to move both ends of said member in unison, a three-legged differential, two drives for driving two legs of said differential from opposite ends of said member to thereby cause the third leg of said differential to move in response to the ends of said member moving through different distances, means for further adjusting at least one of said valves in response to movement of the third leg of said differential to thereby correct any variation in the movement of one end of said member relative to the movement of the other end of said member, and means for causing one motor to operate independently of the other motor and move one end of said member relative to the other end thereof including means for restraining one leg of said differential from rotating and means for rendering ineffective the drive connected to that leg.
20. The combination with two hydraulic motors and means for supplying motive liquid to said motors to energize the same and including means for controlling the flow of liquid to each motor, means for adjusting said flow control means to effect an initial adjustment of one motor relative to the other motor, means for adjusting said flow control means to effect operation of said motors, and means responsive to a variation in the relative speeds of said motors for further adjusting said flow control means to correct such variation in speed.
21. The combination with two hydraulic motors and means for supplying motive liquid to said motors to energize the same, of a control mechanism including means for controlling the flow of liquid to each motor, means for operating said flow control means to effect operation of said motors, means responsive to a variation in the relative speeds of said motors for adjusting said flow control means to correct such variation in speed, and means for adjusting said control mechanism to cause said flow control means to effect an initial adjustment of said motors relative to each other in response to operation of said operating means.

WALTER FERRIS.
